(57) **CLAIM**

We claim the ornamental design for a handle for cooking utensil, as shown and described.

DESCRIPTION

FIG. 1 is a front elevational view of a handle for cooking utensil of one embodiment of the claimed design;

FIG. 2 is a perspective view of the handle for cooking utensil shown in FIG. 1;

FIG. 3 is a rear elevational view of the handle for cooking utensil shown in FIG. 1;

FIG. 4 is a right side elevational view of the handle for cooking utensil shown in FIG. 1;

FIG. 5 is a left side elevational view of the handle for cooking utensil shown in FIG. 1;

FIG. 6 is a bottom plan view of the handle for cooking utensil shown in FIG. 1;

FIG. 7 is a top plan view of the handle for cooking utensil shown in FIG. 1;

FIG. 8 is a top plan view of a handle for cooking utensil of another embodiment of the claimed design;

FIG. 9 is a perspective view of the handle for cooking utensil shown in FIG. 8;

FIG. 10 is a rear elevational view of the handle for cooking utensil shown in FIG. 8;

FIG. 11 is a left side elevational view of the handle for cooking utensil shown in FIG. 8;

FIG. 12 is a right side elevational view of the handle for cooking utensil shown in FIG. 8; and,

FIG. 13 is a bottom plan view of the handle for cooking utensil shown in FIG. 8.

The ornamental design which is claimed is shown in solid lines in the drawings. The broken lines in the drawings are for illustrative purposes only and form no part of the claimed design.
